UNITED STATES PATENT OFFICE.

IRAL MERLIS, OF NEW YORK, N. Y., ASSIGNOR TO KELVIN ENGINEERING CO., INC., OF NEW YORK, N. Y., A CORPORATION OF DELAWARE.

EVAPORATOR.

Application filed May 5, 1926. Serial No. 106,922.

The present invention relates to improvements in evaporators and more particularly to the calandria or heat belt thereof.

The invention has for an object to provide an improved baffle arrangement in the steam belt which will cause the steam or vapor to follow a prescribed path which is direct and most efficient.

A further object of the invention resides in providing an improved construction of calandria in which the incondensable gases are trapped at numerous points where they are rapidly drawn off, and in which the drains are symmetrically located with reference to the baffle arrangement whereby to discharge the water through the shortest possible path.

A still further object of the invention lies in providing a simply constructed and compact calandria in which the calandria will be reinforced by the bottom of the evaporator.

With the foregoing and other objects in view, the invention will be described in detail hereinafter, and referred to more particularly in the subjoined claims.

The invention will be described in connection with the accompanying drawings, in which like parts are referred to by the same reference characters, and in which—

Figure 1 is a vertical section taken through a portion of an evaporator showing the improved calandria; and,

Figure 2 is a horizontal section taken on the line 2—2 in Figure 1.

Referring more particularly to the drawings, 3 designates generally the evaporator having the bottom 4; and 5 and 6 designate the tube sheets of the calandria or steam belt. The tubes themselves are indicated at 7.

In accordance with the invention, the steam or vapor is introduced through the inlets or ports 8 and 9, which ports are located in the same diametrical line. In other words, steam or vapor is brought into the cylindrical calandria at two diametrically opposite points and is circulated through the tubes in a number of paths as required by the arrangement of the baffles. The lateral baffle plates 10 and 11 are also located on the same diametric line or are arranged diametrically opposite one another and have their outer edges flush against the shell 12 of the

heat belt, the upper and lower edges being fitted against the respective tube sheets 5 and 6. The inner edges of the baffle plates 10 and 11 terminate short of one another and of the down-take 13 to enable the steam and vapor to have free passage at opposite sides of the down-take. The diametric line joining the lateral baffle plates 10 and 11 is at 90° to the diametric line joining the inlet ports 8 and 9.

In addition to the lateral baffles, there are also provided diagonal baffles made up of the companion angularly arranged plates 14, 15 and 16, 17. These intermediate or diagonal baffles, like the lateral baffles, are of the same height as the calandria and fitted at their upper and lower edges against the tube sheets 5 and 6 to which they may be attached as by bolting, riveting, brazing or the like. The adjacent ends of the intermediate or diagonal baffle plates 14 and 15 are flanged and secured together as indicated at 18 and the baffles are closed at this point, this connection lying in the diametric line connecting the axes of the steam inlet ports 8 and 9, whereby the steam blowing in through the inlet port will meet the flanges 18 and be divided thereby and deflected to opposite sides of the flanges and against the two diagonally disposed baffle plates. The flanges 18 may be secured together in any desired manner. The diagonal plates 14 and 15 converge toward the steam inlet 8 and at their inner sides form an obtuse angular corner in which is placed the perforated vent pipe 19. This perforated pipe, as shown in Fig. 1, extends up through the top tube sheet 5 and is coupled to a pipe 20 for carrying off the incondensable vapors.

In a similar way the opposite companion diagonal baffle plates 16 and 17 are arranged at the same obtuse angle and within this angle is arranged a similar perforated pipe 21 passing up through the upper tube sheet and connected either to the same pipe 20 or to a separate pipe.

At opposite sides of the lateral baffle 10 near the shell 12 are provided similar perforated vent pipes 22 and 23. Similar vent pipes 24 and 25 are located at the opposite side of the apparatus and to opposite sides of the lateral baffle 11 near the outer shell 12.

At an intermediate point of the diagonal baffle plates 14 and 15 are the drains 26 and

27 and similar drains 28 and 29 are provided beneath the opposite diagonal baffle plates 16 and 17, these drains being of sufficiently large diameter to extend on both sides of the 5 baffle plates. Where the baffle plates are provided with flanges for fitting against the upper and lower tube sheets, such flanges are removed or cut away at the drains. These 10 drain pipes, as shown in Fig. 1, extend down from the bottom tube sheet 6 through the bottom 4 of the evaporator. Gaskets 30 of Monel metal, preferably corrugated, are used at the joints where the drain pipes pass through the evaporator bottom 4 and join 15 with the bottom tube sheet 6 of the calandria. These gaskets will take up the strains due to expansion and contraction of the different metals, as the calandria plates and tubes are of copper and the bottom 4 of cast iron.

20 The steam entering the inlet port 8 will encounter the V-shaped plates 14 and 15 and be divided into the two streams; one stream being diverted in one circumferential section between the baffle plate 14 and calandria 25 shell while the other stream proceeds in the opposite circumferential direction between the baffle plate 15 and shell. These two streams proceed until they encounter the lateral baffle plates 10 and 11 which project 30 directly across their paths. These lateral baffle plates are also spaced from the free ends of the diagonal baffle plates and the streams of vapor or steam are caused to be deflected by the lateral baffle plates into the 35 V-shaped spaces set off by the diagonal baffle plates. The steam coming in the opposite inlet port 9 divides in a similar way and so that the steam is distributed around the tubes in a short and direct path.

40 The location of the collectors or perforated vent pipes for the incondensable gases is such that the gases developed during the first part of the travel of the vapor are removed at the points 22, 23 and 24, 25. The 45 remainder of the incondensable gases developed are completely eliminated at the points 19 and 21. This arrangement of the vent pipes is very important when taken in connection with the baffle arrangement as it 50 enables the gases to be removed as they are developed along the path of the vapor. It will be noted that the outlets 22, 23, 24, 25, are located at pockets where the incondensable gases will naturally accumulate on account of the location of the lateral baffles 10 and 11 and the path of the vapor as it turns around the diagonal baffles.

55 The final gases are chased toward the outlets 19 and 21, which are located at the junction of the diagonal baffles, where the final gases will naturally collect and will be completely removed.

60 The location of the various drains is symmetrically and equi-distant from the center 65 and from the various points where the

various vapors are apt to collect, thus discharging the water through the shortest possible path.

The symmetrical disposition of the drains serves to strengthen the calandria and eliminates the necessity of using tie-rods or other strengthening devices. These collectors tie the bottom of the calandria to the bottom of the vessel and thus serve the double purpose of draining and supporting and tying 75 together the calandria and the bottom of the vessel.

It is obvious that various changes and modifications may be made in the details of construction of the above specifically described embodiment of this invention without departing from the spirit thereof, such changes and modifications being restricted only by the scope of the following claims.

Having thus described the invention, what I claim and desire to secure by Letters Patent of the United States is:—

1. A calandria belt for evaporators having opposite vapor inlets and including diagonal baffles having their convergent portions disposed in the path of the incoming vapor, whereby to divide it into oppositely flowing circumferential streams, and lateral baffles disposed to catch said circumferential streams and to divert the same to the opposite sides of said diagonal baffles.

2. A calandria belt for evaporators having oppositely disposed steam inlets and including diagonal baffles joined in V-shaped arrangement with the joined portions thereof presented to the inlets to divide the steam into two oppositely flowing streams, lateral baffles positioned to intercept the streams at opposite sides thereof from opposite inlets and to deflect the streams on the inner sides of the diagonal baffles whereby to cause the streams to follow a short and direct path through the tubes.

3. A calandria belt for evaporators having oppositely disposed steam inlets, diagonal baffles connected angularly for intercepting the steam and dividing it into two oppositely flowing streams, lateral baffles for intercepting said streams beyond the ends of the diagonal baffles and for deflecting said streams upon the opposite sides of said diagonal baffles, and vents for the incondensable gases positioned near the outer ends of said lateral baffles.

4. A calandria belt for evaporators having oppositely disposed steam inlets, diagonal baffles connected angularly for intercepting the steam and dividing it into two oppositely flowing streams, lateral baffles for intercepting said streams beyond the ends of the diagonal baffles and for deflecting said streams upon the opposite sides of said diagonal baffles, and vents for the incondensable gases located at the inner angular meeting points of said diagonal baffle plates.

5. A calandria belt for evaporators having oppositely disposed steam inlets, diagonal baffles connected angularly for intercepting the steam and dividing it into two 5 oppositely flowing streams lateral baffles for intercepting said streams beyond the ends of the diagonal baffles and for deflecting said streams upon the opposite sides of said diagonal baffles, vents for the incondensable gases located in the corner portions between the lateral baffles and calandria shell and in the corner portions between the meeting edges of the diagonal baffles.

IRA MERLIS.
